UNITED STATES PATENT OFFICE.

MICHAEL A. LYNCH AND JOHN P. F. WHITE, OF WASHINGTON, DISTRICT OF COLUMBIA.

CLOSURE FOR TANKS.

1,308,794.

Specification of Letters Patent.

Patented July 8, 1919.

Application filed March 23, 1918. Serial No. 224,194.

To all whom it may concern:

Be it known that we, MICHAEL A. LYNCH and JOHN P. F. WHITE, both of Washington, District of Columbia, have invented 5 certain new and useful Improvements in Closures for Tanks, and we do hereby declare the following to be a full, clear, and exact description of the invention, such as will enable other skilled in the art to which 10 it appertains to make and use the same.

Our invention relates to closures for tanks and particularly to such as are used in connection with powder tanks where a complete sealing of the container is necessary to protect the contents. Tanks adapted for this purpose are ordinarily made of metal and it is well known that in order to secure an air-tight seal in closing these tanks gaskets of leather or other material must be interposed between the closure and the tank at 20 the point of contact between these two elements. It is also well known that such gaskets deteriorate in use. The object of our invention is to provide an improved, simple 25 and highly efficient mechanism for rendering the closure of powder tanks air-tight and for compensating for the deterioration of the gasket.

In the accompanying drawings, Figure 1 30 is a fragmentary sectional view of a portion of a tank showing our improved closure. Fig. 2 is a top plan view. Fig. 3 is an enlarged fragmentary sectional view. Fig. 4 is a similar view showing a modified form 35 of lever arm. Figs. 5 and 6 are fragmentary sectional views showing slight modifications of the locking means. Fig. 7 is a top plan view of the knee and a portion of the lever arm shown in Fig. 6.

Referring to Figs. 1 to 4, inclusive, we 40 have shown at 1 a portion of a powder tank which is formed of sheet metal, a head 2 being welded or otherwise secured to the tank. This head has a portion 3 of ring-form 45 extending above the upper edge 4 of the tank and spaced therefrom a slight distance. 5 indicates the cover for the tank. This cover is preferably formed of sheet metal and has at its peripheral edge and 50 on its underside an annular groove 6 to accommodate a gasket 7 of rubber, or other material which is adapted to coöperate with the upper edge 4 of the tank, the edge forming a seat for the cover. Disposed centrally 55 of the latter is an upwardly extending post 8 which has a base 9 fixedly secured thereto,

Above the cover we provide a locking member 10 which is preferably of spider form, the legs 12 being adapted for locking engagement with spaced inwardly extending 60 plates 13 secured to the inner side of the ring-like portion 3 of the head. The upper face of the legs 12 is inclined from one side to the other to insure a wedging engagement with the plates 13. The locking member is 65 centrally apertured at 14 to receive an exteriorly threaded sleeve 15 which is adapted to be rotated about the post 8. Coöperating with this sleeve 15 and located between the locking member and the cover is a nut 16 70 to which are secured a plurality of presser arms or levers 17 preferably formed of spring metal. These arms are designed to engage the cover 5 adjacent its outer edge 75 and directly above the groove and gasket so as to effect a firm seating of the cover on the upper edge 4 of the tank. The number of presser arms preferably corresponds to the number of legs of the locking member. The latter have downwardly extending 80 flanges 13' to prevent turning of the arms 17 relatively to the legs 12. These flanges also materially add to the strength of the locking member. Each arm at its inner end fits between upper and lower plates 18 and 85 19 of the nut 16, and the arms have a slight vertical play between these plates to which they are secured by a ball and socket connection 20. The presser arms or levers extend upwardly and outwardly from their 90 connection with the nut 16 and at a point 21 near their outer ends are bent slightly downward the extreme outer end 22 of the arm bearing on the upper face of the cover 95 directly over the gasket 7. The point 21 of each lever arm bears against the under-face of its complementary leg 12 this point forming the fulcrum of the arm. It is manifest that the distance between the extreme outer end of each arm and the point 100 21 may be altered to provide greater or less leverage as the size of the closure may require.

The threaded sleeve 15 is provided with any preferred turning element, such as 105 wings 23. By reason of the formation of the arms 17 as before described, each arm acts as a lever to force the cover down on to the tank, as the nut 15 is raised on the sleeve 16, thus effecting a relative movement 110 between the cover 5 and the locking member 10. It is manifest that but slight move-

ment of the nut 16 on the sleeve 15 will apply sufficient pressure to the edge of the cover to cause the latter to be firmly seated on the upper edge of the tank.

- 5 It is apparent that equally advantageous results may be secured by forming, as shown in Fig. 4, the nut 26 and presser arms 27 from a single piece of metal, the bore 28 being threaded to engage the sleeve 15. Leverage mechanism such as shown in this figure is capable of producing the same effective results as the form wherein the presser arms are movably secured to the nut 16.

In applying the cover to the tank it is only necessary to turn the parts so that the legs of the locking member are out of line with the inwardly projecting plates 13. The cover is then pressed down upon its seat and the locking member turned so that its legs 20 will wedge under the plates 13. By turning the sleeve 15 to the right the nut 16 will work up on the sleeve causing the arms 17 to fulcrum about the points 21, such movement of the arms effecting downward movement of the extreme outer ends 22 and a consequent application of pressure to the peripheral portion of the cover which is thereby moved relatively to the locking member 10. By reason of the resiliency of 30 the arms, this pressure will be constant thus effectively sealing the cover to the tank and compensating for any deterioration which may occur in the gasket. The power for raising the spring arms and consequently 35 securing greater pressure between the edge of the tank and the cover may be exerted on the cover at its center or on the spider, or it may be distributed between the cover and the spider. It will be apparent that 40 pressure within the tank will have a tendency to force the center of the cover upwardly and such upward movement will give greater power to the leverage mechanism.

In Fig. 5 we have shown the tank 31 provided with a head 32 adjacent the upper edge 34 thereof, this edge forming a seat for the cover 35. At spaced intervals around the head 32 are headed lugs 36 adapted for locking engagement with a casing 37 through bayonet slots 38, the casing forming a housing for the cover 35 and the leverage mechanism by which the cover is seated on the tank. As shown, the casing has a central depression 39 within which the 50 manipulating nut 40 is received so as to prevent any projection beyond the upper horizontal plane of the casing, enabling the tanks to be superposed one upon the other. The inner face of the depressed portion forms 55 a fulcrum bearing for the lever arms 41.

In Fig. 6, the tank 51 has an encircling band 52 which strengthens the upper edge of the tank, the latter forming a seat for the cover 53. The means for locking this 60 cover to the tank includes a ring 54 having

a number of bayonet slots 55 which take in lugs 56 struck up from the band 52. Secured to and projecting inwardly of the ring and near its upper edge are a plurality of knees 57 each of which has webs 58 to give 70 additional strength. Ears 59 depending from these knees at each side and connected by a short rod 60 form a retaining means for the lever arms 61 which latter have their fulcrum on the under face of the knees. 75

The cover shown in Figs. 5 and 6 is readily attached to the tank by simply alining the open ends of the bayonet slots with the locking lugs and crowding the casing or housing down and then turning the latter so 80 as to positively lock it to the tank. The cover is then firmly seated in the manner described with reference to the form shown in Figs. 1 to 4.

The advantages of our invention will be 85 apparent. It will be seen that by the very simple construction embodied in our cover we are enabled to secure a perfect sealing of a tank, pressure being always exerted upon the cover directly above its engagement with 90 the tank. The parts forming the cover are simple and are not liable to readily get out of order.

We claim as our invention:

1. In combination with a tank, and a cover 95 adapted to be seated on said tank, locking means including coöperating elements for securing said cover to the tank, and a plurality of arms movable relatively to said locking means for causing said cover to be 100 firmly seated on the tank.

2. In combination with a tank, and a cover adapted to be seated on said tank, locking means including coöperating elements for securing said cover to the tank, and a plurality of spring arms for forcing said cover 105 to its seat, said arms bearing on said cover adjacent the point of engagement of the latter with the tank.

3. In combination with a tank, and a cover 110 adapted to engage the upper edge of such tank, means for locking said cover to the tank including coöperating elements, and means intermediate said locking means and said cover including a plurality of arms for 115 causing the cover to be firmly seated upon the tank.

4. In combination with a tank, and a cover for said tank adapted to engage its upper edge, means for locking said cover to said 120 tank including coöperating elements, means intermediate said locking means and said cover having arms adapted to engage said cover and said locking means to effect a relative movement therebetween to cause the 125 cover to be firmly seated upon the tank.

5. In combination with a tank having its upper portion formed with a valve seat, and a cover for said tank adapted to engage said seat, a spider-like member for locking said 130

- cover to said tank, and a second spider-like member intermediate said locking spider and said cover for effecting a relative movement therebetween to cause the latter to be firmly seated upon said tank.
6. In combination with a tank having its upper portion formed with a valve seat, and a cover for said tank adapted to engage said valve seat, an upwardly extending ring-like member surrounding said seat and spaced therefrom, said ring-like member having inwardly extending spaced apart portions, a member having a plurality of legs for co-operating with said inwardly extending portions to lock said cover to said tank, and a leverage mechanism intermediate said locking member and said cover for effecting a relative movement therebetween to firmly seat the latter upon said tank.
- 10 7. In combination with a tank having its upper portion formed with a valve seat, and a cover for said tank adapted to engage said valve seat, an upwardly extending ring-like member surrounding said seat and spaced therefrom, said ring-like member having portions forming part of a locking element, a member having a plurality of legs for co-operating with said ring-like member to lock said cover to said tank, and a leverage mechanism intermediate said locking member and said cover for effecting a relative movement therebetween to firmly seat the latter upon said tank.
- 15 8. In combination with a tank having a valve seat at its upper end, and a cover having a portion adapted to engage such valve seat, locking means including co-operating elements for securing the cover to the tank, a leverage mechanism interposed between said cover and said locking means, and means for actuating said leverage mechanism to cause the seating of said cover on the tank.
- 20 9. In combination with a tank having a valve seat at its upper end, and a cover having a portion adapted to engage such valve seat, locking means including co-operating elements for securing the cover to the tank, a support and said locking means, a support common to said arms, and means for actuating said support to cause the seating of said cover on the tank.
- 25 10. In combination with a tank having a valve seat at its upper end, and a cover having a portion adapted to engage such valve seat, locking means including co-operating elements for securing the cover to the tank, a plurality of arms interposed between said cover and said locking means, a support to which said arms are movably connected at their inner ends, and means for actuating said support to cause the seating of said cover on the tank.
- 30 11. In combination with a tank having a valve seat at its upper end, and a cover having a portion adapted to engage such valve seat, locking means including co-operating elements for securing the cover to the tank, a plurality of arms interposed between said cover and said locking means, a support to which the inner ends of said arms are secured by ball and socket connection, the outer ends of said arms being adapted to bear upon said cover, and means for actuating said support to cause the seating of said cover on the tank.
- 35 12. In combination with a tank having a valve seat at its upper end, and a cover having a groove and a gasket in said groove adapted to engage said valve seat, an upwardly extending-centrally-disposed post on said cover, a manually operable screw threaded sleeve surrounding said post, a member for locking the cover to the tank, said member having an opening at its center through which said post and sleeve extend, a plurality of lever arms interposed between said cover and locking member and fulcrumed on the latter, and a connection between said lever arms and sleeve whereby the arms may be moved on their fulcrums to exert pressure on said cover.

In testimony whereof, we have signed this specification.

MICHAEL A. LYNCH.
JOHN P. F. WHITE.
